Int. Cl. D14—02

U.S. Cl. D16—1 A

FIG. 1 is a perspective view of the instrument tray for use in hospitals or the like showing our new design; and FIGS. 2 and 3 are respectively top plan and side elevational views thereof.

The broken lines shown in FIG. 1 are intended to depict the continuous appearance of all adjacent elements.

We claim:

The ornamental design for an instrument tray for use in hospitals or the like, substantially as shown and described.
